(57) **CLAIM**

The ornamental design for a light fixture, as shown and described.

DESCRIPTION

FIG. 1 is a perspective view of a light fixture of the present invention;

FIG. 2 is a bottom plan view of the light fixture of FIG. 1; FIG. 3 is a cross-sectional view of the light fixture of FIG. 1 taken along the line 3-3 in FIG. 2; and,

FIG. 4 is a cross-sectional view of the light fixture of FIG. 1 taken along the line 4-4 in FIG. 2.

FIGS. 1, 2 and 4 are broken away to indicate indeterminate length. The broken lines are shown in FIGS. 1, 3, and 4 for illustrative purposes only and form no part of the claimed design. The top of the light fixture is unornamented and forms no part of the design.
